CLAIM

The ornamental design for an adapter plate for vacuum cleaner as shown and described.

DESCRIPTION

FIG. 1 is a perspective view of an adapter plate for vacuum cleaner showing the new design.

FIG. 2 is a front view thereof.

FIG. 3 is rear view thereof.

FIG. 4 is a right-side view thereof.

FIG. 5 is a left-side view thereof.

FIG. 6 is a top view thereof; and,

FIG. 7 is a bottom view thereof.

In these drawings, the solid lines illustrate the claimed ornamental design, whereas broken lines, if present, illustrate unclaimed subject matter and form no part of the claimed design.

1 Claim, 7 Drawing Sheets
